[57] **CLAIM**

The ornamental design for sun glasses, as shown and described.

DESCRIPTION

FIG. 1 is a front elevational view of the sun glasses showing my new design;

FIG. 2 is a top plan view thereof;

FIG. 3 is a left side elevational view thereof, the right side being a mirror image;

FIG. 4 is a rear elevational view thereof;

FIG. 5 is a bottom plan view thereof.

A side view of the sun glasses taken with respect to the right side of FIG. 1 would be a mirror image of FIG. 3.

FIG. 1

FIG. 2

FIG. 3

FIG. 4

FIG. 5
